FLUID OPERATED VIBRATOR

Ralph Burt, Homer City, Pa., assignor to Sytron Company, Homer City, Pa., a corporation of Delaware

Application August 14, 1945; Serial No. 610,852

10 Claims. (Cl. 259—1)

1

The present invention relates to fluid operated vibrators, particularly adapted for attachment to hoppers, bins, chutes, or tables or the like, for vibrating the object to which it is attached by the reactive forces developed.

It is an object of the present invention to provide a fluid operated vibrator that may be operated directly by fluid under pressure.

Another object is the provision of a fluid operated vibrator having an adjustable amplitude and period of vibration.

Another object is the provision of a fluid operated vibrator having a wide range of frequencies of operation, and which is of relatively simple construction and is compact.

Another object is the provision of a fluid operated vibrator wherein the adjustment for the period and amplitude of vibration is located exterior of the fluid chamber and is readily accessible.

A further object is the provision of a fluid vibrator having a resilient connection between the valve and diaphragm, whereby a relatively simple mechanism may be employed to secure the desired vibration.

In accordance with the present invention, I provide a vibrator having a relatively light base adapted to be secured to an object to be vibrated and carrying a chamber which is closed by a pliable diaphragm connected to a control valve in the chamber by a yieldable or resilient linkage, whereby the control valve may move with a snap action to control the period of vibration and amplitude of the stroke of the diaphragm. A massive member is secured to the diaphragm, preferably by a rigid connection and a pivot at one end to allow for slight out of line movement, and I prefer to employ external springs to bias the member so that its amplitude of vibration and frequency of vibration may be adjusted.

The invention will be described in greater detail in the following specification taken in connection with the accompanying drawings, wherein I have shown preferred embodiments of the invention by way of example, and wherein:

Figure 1 is a vertical longitudinal section through a preferred embodiment of the invention;

Figure 2 is an end view of Figure 1;

Figure 3 is a sectional view of a detail;

Figure 4 is a view partly in vertical section of a further embodiment of the invention, and

Figure 5 is a side view of another embodiment of the invention.

Referring to the drawing, Figure 1, there is shown a base 1 of any suitable size or shape having

holes 2 formed at its ends whereby the vibrator may be secured to the object or apparatus to be vibrated. The base has a central boss 3 which is bored at 4 to provide a pressure chamber having an inlet connection 5. The inlet 5 is shown displaced about 90° from its normal position to simplify the drawing. A cross bore 6 connecting with a vertical bore 7 provides an outlet for chamber 4 and is controlled by a valve member 8 adapted to seat against a tapered seat 11 surrounding the bore 7 when in closed position.

The upper end of chamber 4 is closed by a diaphragm 12 clamped at its periphery to the boss 3 by an annulus 13 and bolts 14. The diaphragm 12, which may be of any suitable material, is clamped between plates 15 and 16 by screws 17 passing therethrough, and the plate 16 has an extension 18 which has a bore at 21 to receive a tight fitting grommet 22 of rubber or other suitable resilient material, such as polymerized butadiene, copolymerized butadiene and styrene or acrylonitrile, and polymerized methylchlorobutadiene, known commercially as "Ameripol" or "neoprene." A sleeve 23 is provided in the grommet. The valve member 8 is secured to a bifurcated rod or clevis 24 by means of a screw 25 and nut 26, which also serves to hold a castellated guide member 27 in place. The upper end of clevis 24 is bored to receive a bolt 28 passing therethrough and through the sleeve 23 in the grommet 22, whereby the valve 8 is resiliently or yieldably tied to the diaphragm 12.

The upper plate 15 carries a massive member 31 secured thereto by one or more cap screws 32, and which may be designated as the vibratory portion of the vibratory motor. The member 31 is supported by two sets of leaf springs 33 clamped thereto at the middle by clamps 34, and secured at their ends to the base 1 by clips 35 which allow the intermediate portion of the springs to flex and guide the member in its vibratory motion. The member 31 is bored at 36 and 37 to receive helical springs 41 and 42 compressed by means of washers 43, studs 44, 45 and nuts 46. The period of vibration of the member 31 at a given water pressure is determined partly by its mass and partly by the compression of springs 41 and 42, and to some extent by the springs 32 and 33. The period of vibration thus may be varied by adjusting nuts 46 which are external of the pressure chamber; an increase in compression of springs 41, 42 tending to increase the period of vibration.

In operation, the fluid, which preferably is water under pressure, is admitted to chamber 4

through inlet 5 and exerts a pressure on the under side of diaphragm 12 which tends to raise the diaphragm and distort the grommet 22. The area of diaphragm 12 is greater than the area of the valve opening 7, and a ratio of about 10 to 1 to 13 to 1 has been found preferable, although this ratio may be varied for different water pressures, and other suitable ratios may be employed. At the same time that fluid pressure is raising the diaphragm it is also acting on the upper area of valve 8 to hold it on its seat against the action of distorted grommet 22 which tends to assume its normal position until finally the restoring force of the distorted grommet and the upward force on the diaphragm are sufficient to lift the valve off its seat, thus exposing outlet 7 to relieve the pressure in chamber 4 and allowing restoration of grommet 22. The drop in pressure in chamber 6, the mass 31, and the springs 32, 33, 41 and 42 will cause the diaphragm to move downwardly when the pressure in chamber 4 has been reduced sufficiently, and carry the valve to its seat. The flow of fluid past the valve 8, which occurs when the valve is near its seat, tends to produce fluttering or chattering of the valve, and resilient grommet 22 reduces or prevents fluttering of the valve, insures proper closing thereof, and cushions the downward impact of the mass 31 against the valve and seat. The closing of valve 8 allows the pressure in chamber 4 to build up and again raise the diaphragm, to repeat the cycle of operation and thus cause vibration of the mass 31. A simultaneous vibration in base 1, which is less massive than member 31, and which is secured to the object which it is desired to vibrate, such as a bin, hopper, chute, trough or table or the like, causes the object to vibrate.

The frequency and amplitude of vibration depends on several factors including the strength of springs 33, 32, 42 and 41, the mass of member 31, the stiffness and resiliency of grommet 22, the relative areas of diaphragm 12 and valve 8, the pressure of the fluid supplied, and the rate of flow of fluid provided. The latter may be controlled by a suitable throttle valve preferably located in the outlet and set to allow a nearly uniform flow through the outlet and thus prevent substantial back pressure surges tending to cause fluttering of valve 8. If desired, an air chamber may be connected in the inlet line to cushion pressure surges. The springs 41 and 42 allow the vibrator to be used in any position, as the apparatus does not depend on gravity to return the mass 31 in each cycle, and springs 32 and 33 serve as guides to maintain the mass 31 in proper position. By adjusting springs 41 and 42 the frequency and amplitude of vibration of the mass 31 may be varied. The frequency of vibration also may be controlled by controlling or restricting the rate of flow of fluid supplied through the inlet connection by a suitable valve in the inlet line (not shown) or by restricting or varying the flow through the outlet by a suitable throttle valve in the outlet connection (not shown) or by both. While I have shown a statically unbalanced valve at 8, it will be understood that any suitable type of valve may be employed.

In the modification shown in Figure 4, wherein like parts are designated by like reference numerals, the base 1 is made separate from the part 3 and is secured thereto by bolts or the like passing through the holes 50 into chamber member 3. The member 3 provides a pressure chamber 4 which is closed at its upper end by the pliable diaphragm 12 clamped to the upper end

by clamping ring 13 and bolts 14. The base 1 has a lug 51 and a flexible strap or leaf spring 52, preferably of spring steel, is clamped at one end to lug 51 and its other end is secured to one end of member 31. The flanged backing member 54 has a bore 55 therein which receives a stud 56 threaded therein and passing through diaphragm 12 into bore 55' in backing plate 15, whereby the diaphragm is clamped between the backing plate 54 and block 15. Backing plate 54 has a bore 58 in which is located a washer 60 of natural or synthetic rubber material. A valve stem 61 has a plate 62 held against a shoulder thereon adjacent one end by the nut 63, this plate being received in the bore 58. A second washer 65 of solid resilient material is located on the opposite side of plate 62, and a metal plate 66 is secured to the backing plate 54 by screws 68 or the like so that the plate 62 and valve stem 61 are resiliently and firmly held between the washers 60 and 65.

A clearance space is provided around the inside of washers 60 and 65 to allow deformation thereof to take place during operation of the apparatus, and a suitable clearance for plate 62 is allowed to prevent binding thereof in bore 58, and the central bore 70 in plate 66 is large enough to allow lateral movement of stem 61 without binding.

The valve stem 61 extends through a suitable hole 70 in plate 66 and at its opposite end carries a valve member 8 which may be locked thereon between a lock nut 71 and a castellated or cup shaped wing guide member 27 held thereon by a screw 72. A suitable inlet 5 is provided in the side of chamber 4 for the introduction of working fluid under pressure, and a recess or well 7 is provided in the chamber with which the outlet 6 communicates. A valve seat member 73 of suitable material has a valve aperture 74 and a tapered seat 75 surrounding the aperture which is adapted to cooperate with the tapered portion 40 45 50 55 60 65 70 75 80 85 90 95 76 of the valve member, the guide 27 being of such dimensions as to move freely through the bore 74 and at the same time prevent excessive lateral movement of the valve, so that the valve properly seats on its downward stroke. A cushion to eliminate water hammer is provided by the hollow tubes 77 and 78 surrounding the plate 54, the tubes being made of deformable resilient material, such as rubber, and containing trapped air so as to cushion the water hammer. A member 31 is secured at one end to the strap 52 and is secured by cap screws 89 to the block 15. The base 1 has a post 82 threaded into the base and is held in place by a lock nut 83. The post extends through a suitable hole 84 in member 31 surrounded on either side by recesses 85 and 86, and a spring 87 in recess 85 surrounds the post and abuts a washer 93 at one end and the base of the recess 85 at its other end, the washer being located on the post by a lock nut 91. A second spring 88 at one end abuts the washer 93 at one end and the base of recess 86 at its other end, the washer 93 being retained in position on the post by the lock nuts 91. The compression 65 of the springs 87 and 88 may be adjusted by adjusting the positions of the washers 90 and 93.

The operation of this modification is similar to that illustrated in Figures 1 to 3, and it is to be observed that by reason of the pivoted mounting of the member 31 and the relatively large mass 31 at the opposite end of this member, an amplification of vibration is obtained.

In the modification illustrated in Figure 5, wherein like parts are designated by like reference characters, the construction and operation

is similar except that only one spring 87 is located in the recess 85, this spring biasing the member 31 in a direction to cause valve 8 to close when there is no pressure in chamber 4.

The invention may be embodied in other modifications without departing from the spirit or scope thereof.

What I claim as my invention and desire to secure by Letters Patent of the United States is:

1. Vibratory apparatus comprising a base 10 adapted to be secured to an object to be vibrated, and providing a pressure chamber, a pliable diaphragm closing one end of said chamber, inlet and outlet connections to said chamber, a valve for controlling flow through said outlet connection, resilient means connecting said valve and diaphragm, a massive body connected to said diaphragm, and spring means biasing said mass and diaphragm in a direction to close said valve.

2. Vibratory apparatus comprising a base adapted to be secured to an object to be vibrated and providing a pressure chamber, a pliable diaphragm closing one end of said chamber, inlet and outlet connections to said chamber, a valve for controlling flow through one of said connections, resilient means connecting said valve and diaphragm, a massive body secured to said diaphragm, and flexible means to support and guide said body in its vibratory movement.

3. Vibratory apparatus comprising a base adapted to be secured to an object to be vibrated and providing a pressure chamber, a pliable diaphragm closing one end of said chamber, inlet and outlet connections to said chamber, a valve for controlling flow through said outlet connection, resilient means connecting said valve and diaphragm, a massive member secured to said diaphragm, flexible means to support and guide said member, and spring means biasing said member in a direction to close said valve.

4. Vibratory apparatus comprising a base adapted to be secured to an object to be vibrated and providing a pressure chamber, a pliable diaphragm closing one end of said chamber, inlet and outlet connections to said chamber, a valve for controlling flow through one of said connections, resilient means connecting said valve and diaphragm, a massive member secured to said diaphragm, means providing a movable pivot for said member, and spring means on opposite sides of the member exterior of said pressure chamber.

5. Vibratory apparatus comprising a base adapted to be secured to an object to be vibrated and providing a pressure chamber, a pliable diaphragm closing one end of said chamber, inlet and outlet connections to said chamber, a valve for controlling flow through one of said connections, resilient means connecting said valve and diaphragm, a massive member secured to said diaphragm, a cantilever spring secured to said base and member providing a movable pivot for the latter, and spring means on opposite sides of the member exterior of said pressure chamber.

6. Vibratory apparatus comprising a base adapted to be secured to an object to be vibrated and providing a pressure chamber, a pliable diaphragm closing one end of said chamber, inlet and outlet connections to said chamber, a valve

for controlling flow through said outlet connection, resilient means connecting said valve and diaphragm, a massive member secured to said diaphragm, a cantilever spring secured to said base and member providing a movable pivot for the latter, and spring means biasing said member in a direction to close said valve.

7. Vibratory apparatus comprising a base adapted to be secured to an object to be vibrated and providing a pressure chamber, a pliable diaphragm closing one end of said chamber, inlet and outlet connections to said chamber, a valve for controlling flow through said outlet connection, resilient means connecting said valve and diaphragm, a massive member secured to said diaphragm, a leaf spring secured to said base and to said member, spring means biasing said member in a direction to close said valve, and a hollowair cushion chamber member in said pressure chamber.

8. Vibratory apparatus comprising the base adapted to be secured to an object to be vibrated and providing a pressure chamber, a pliable diaphragm closing one end of said chamber, inlet and outlet fluid pressure connections to said chamber, a valve for controlling the flow of fluid through one of said connections, a block secured to the diaphragm, a mass resiliently supported relative to the base and attached to said block, resilient means interposed between said block and said valve to delay the operation of the valve and cause the mass to vibrate.

9. Vibratory apparatus comprising the base adapted to be secured to an object to be vibrated and providing a pressure chamber, a pliable diaphragm closing one end of said chamber, inlet and outlet fluid pressure connections to said chamber, a valve for controlling the flow of fluid through one of said connections, a block secured to the diaphragm, a mass resiliently supported relative to the base and attached to said block, a body of rubber material resiliently connected between said block and said valve to delay the operation of the valve and cause the fluid to vibrate the mass.

10. Vibratory apparatus comprising a base adapted to be secured to an object to be vibrated and providing a pressure chamber, a pliable diaphragm closing one end of said pressure chamber, plate means attached to said diaphragm for movement therewith, an extension on said plate means having a resilient insert, inlet and outlet fluid connections to said chamber, a valve controlling the flow of fluid through one of said fluid connections, a mass resiliently supported relative to the base and attached to said plate means, and means connecting said resilient insert and said valve to delay the operation of the latter and cause the mass to vibrate.
